DISPLAY RACK FOR TAPE CARTRIDGES

Ralph C. Bertanzetti, 4522 Nantucket Blvd.,
Youngstown, Ohio 44515

Filed Apr. 20, 1971, Ser. No. 135,826

Term of patent 3½ years

Int. Cl. D6—04

U.S. Cl. D6—190

FIG. 1

FIG. 3

FIG. 1 is a specified view taken from the top, front and one side of a display rack of tape cartridges embodying my new design;

FIG. 2 is a front elevational view thereof; the rear being substantially plain; and

FIG. 3 is a side elevational view thereof.

I claim:

The ornamental design for a display rack for tape cartridges, substantially as shown and described.
